C. WEINBERG.

GIMP.

No. 18,183.

Patented Mar. 13, 188

UNITED STATES PATENT OFFICE.

CHARLES WEINBERG, OF NEW YORK, N. Y., ASSIGNOR TO C. WEINBERG & CO., OF SAME PLACE.

DESIGN FOR GIMP.

SPECIFICATION forming part of Design No. 18,183, dated March 13, 1888.

Application filed January 16, 1888. Serial No. 260,952. Term of patent 7 years.

To all whom it may concern:

Be it known that I, CHARLES WEINBERG, of the city and State of New York, have invented a Design for Gimp, of which the following is a specification.

In the accompanying photograph three pieces of gimp are shown, and the difference in appearance results from the colors used in the respective pieces.

The design of the pattern consists in the ranges of spiral-cord ornaments 1 and 2, the cord ornament 2 being a series of arcs or scallops in opposite directions along near the edges of the gimp, and in the middle of the gimp are two ranges of cord ornaments, 4, with transverse bars 5, and at the edges of the gimp are small loops 6, and the longitudinal bands 7 are

between the loops 6 and spiral cords 2, and the longitudinal bands 8 are between the spiral-cord ornaments and the cord ornaments 4, 20 and there are short cross-bands to the bands 7 and 8.

I claim—

The design for gimp, substantially as represented, consisting in the design of the spiral-cord ornaments in opposite scallop lines and the intermediate cord ornaments and longitudinal and crossing bands, substantially as represented.

Signed by me this 7th day of January, 1888. 30
CHARLES WEINBERG.
